UNITED STATES PATENT OFFICE

BENJAMIN GEORGE CALL, OF TACOMA, WASHINGTON, ASSIGNOR TO AMERICAN SMELTING AND REFINING COMPANY, OF NEW YORK, N. Y., A CORPORATION OF NEW JERSEY

CALCINE-DUST SEAL

Application filed February 21, 1929. Serial No. 341,640.

This invention relates to ore treating apparatus, and more particularly to a calcine car and to a new and improved dust seal therefor to prevent the escape of dust when the calcine is charged from the car into a furnace.

The invention relates to the treatment of ore, dust or other materials in which the raw material is first roasted in a suitable roasting furnace and then is transferred by means of a calcine car to a smelting furnace. In thus transferring the calcine it is necessary to first fill the car with the calcined material from the roasting furnace and then to move the car to a distant part of the plant where the smelting furnace is located. The material is then discharged directly from the car into the smelting furnace. In making this transfer it is desirable to prevent the escape of dust into the atmosphere in order to prevent a substantial loss of material and to avoid contaminating the air and thereby causing discomfort and injury to operators.

The present invention accomplishes this by providing a seal between the discharge hopper of the calcine car and the feed pipe leading to the furnace. Means is provided whereby a substantially tight seal is automatically obtained and a simple control mechanism is employed for rendering the seal operative. In order to allow the escape of air as the material is discharged a stationary vent pipe is located directly above the charge opening of the furnace and automatic means are provided whereby a tight seal is formed between the vent pipe and the top of the calcine car when the latter is brought into material discharging position.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection

with the accompanying drawings forming a part thereof, in which

Fig. 1 is an elevation of a pair of calcine cars operatively positioned for discharging material into a furnace;

Fig. 2 is an enlarged view partly in section of the lower seal and control apparatus therefor;

Fig. 3 is a section taken on the line 3—3 of Fig. 2 showing the pivoted lever for controlling the seal;

Fig. 4 is an enlarged sectional view of the upper calcine seal showing a portion of the vent at the top of the calcine car;

Fig. 5 is a section taken on the line 5—5 of Fig. 2 showing the control mechanism for the lower seal; and

Fig. 6 is a section taken on the line 6—6 of Fig. 2 showing the details of the lower seal.

Like reference characters denote like parts in the several figures of the drawings.

In the following description and in the claims parts will be identified by specific names for convenience, but they are intended to be as generic in their application to similar parts as the art will permit.

In the drawings accompanying and forming part of this specification, a practical commercial embodiment of the invention is shown, but as such illustration is primarily for purposes of disclosure, it will be understood that the structure may be modified in various respects without departure from the broad spirit and scope of the invention as hereinafter defined and claimed.

Referring more particularly to the drawings, a calcine car 10 is shown in Fig. 1 as supported from a chassis 11 to which wheels 12 are secured for permitting the car to travel over rails 13. The calcine car is in the form of a hopper terminating in a spout 14 which may be closed by a suitable gate 15 (Fig. 2) and is provided with a bottom flange 16 for the purpose to be described. The gate 15 is pivotally secured to framework 20 as by pin 21 and is adapted to slide transversely of spout 14 from open to closed position. Framework 20 is secured to pivoted link 22 (Fig. 1) which is operated by a suitable han-

dle 23 for controlling the position of said gate.

Feed pipe 25 terminates in a nipple 26 which is secured in a charge opening of the furnace 27 which may be of any suitable type. The upper portion of pipe 25 carries a housing 30 (Figs. 2 and 6) having a top flange 31 by means of which it may be secured to a stationary support or platform 32 on which rails 13 are carried. Flange 31 is recessed to slidably receive rods 35. Tubular member 33 is slidably mounted in housing 30 and is provided at its upper end with outwardly extending supports 34, which are carried on the upper end of supporting rods 35. The upper end of sleeve 33 is provided with a circular opening surrounded by a flange 36 having a spherical surface. A complementary dished member 37 is seated on said surface and is provided with a horizontal flange 38 which is adapted to contact with flange 16 of spout 14. The spherical seat permits member 37 to automatically adjust itself to form a tight seal when it is brought into operative relationship with said spout.

Supporting rods 35 are pivotally connected to a lever comprising framework 40 (Figs. 2 and 3). Said framework is provided with collars 41 mounted on rod 42, which is hung from a stationary support 43 by means of depending straps 44. Receptacles 39 are provided on framework 40 to support counterbalancing weights for enabling the device to be more easily operated.

The position of framework 40 is controlled by lever 45 secured to rotating rod 46 (Fig. 5) which is carried in suitable bearings 47 mounted on support 43. A link 48 is secured to said rod 46 and is pivoted to a second link 49 which is slidably mounted in a pivoted support 50. Support 50 is pivotally secured to straps 51 which are carried from the lower portion of framework 40. Spring 52 is carried on link 49 between nut 53 and pivoted member 50. The tension of said spring may be varied by nut 54 which is threaded on said link.

Links 48 and 49 are so related that a toggle action is produced for causing pivotal movement of frame 40 about rod 42 thereby elevating supporting rods 35, causing member 33 to slide upwardly in housing 30, and bringing member 37 into contact with the bottom flange of spout 14. Spring 52 permits the toggle to be moved past its central position whereby the members are automatically locked. The spring furthermore insures a tight contact between flanges 16 and 38 regardless of minor variations in the location of the elements.

The upper part of calcine car 10 is closed by a cover member 60 (Fig. 4) having a central opening therein surrounded by a rectangular flange 61. Strengthening members 62 may extend from said flange to the ends of

the calcine car. Slidable frame 63 is fitted within rectangular flange 61 and is supported from yokes 64 by means of springs 65. Yokes 66 are provided with bolts 67 which extend through cover member 60 and are secured to yoke 64 for limiting the upward movement of the sliding frame 63. The front and rear sides of said frame are provided with curved extensions 70 to facilitate the passage of the framework under stationary vent pipe 71. Said vent pipe may be supported by a suitable bracing member 72 (Fig. 1) and may lead to any desired apparatus which is capable of permitting passage of air while preventing the escape of dust.

In the operation of the above described device, calcine cars 10 are brought into the desired position in alignment with feed pipe 25 and vent pipe 71 for the purpose of discharging calcine into furnace 27. When in this position, lever 45 is utilized for forcing member 33 upwardly and bringing flanges 16 and 38 into contacting relationship the counterbalancing weight in receptacle 39 assisting the operation of the lever. Member 37 then automatically seats due to the spherical contour thereof and causes a tight seal between the feed pipe and the spout to the calcine car.

When the car is brought into the position above described, the bottom portion of the vent 71 contacts with the curved ends of slideable frame 63, thereby depressing said frame and allowing the same to slide under said vent. When the car is in its operative position, frame 63 will be in alignment with the vent 71 and is firmly held against the same by means of spring 65, thereby automatically forming a seal between the opening in the top 60 of the calcine car and the vent pipe. Gate 15 may then be opened by a suitable movement of lever 23 whereby the material within the calcine car is discharged to the furnace while the upper and lower seals above described prevent the escape of dust during the charging operation.

To again remove the car it is only necessary to break the lower seal by a suitable movement of lever 45 thereby releasing the car from contact with the furnace feed pipe. The upper seal is automatically broken as frame 63 slides from under the lower portion of the vent 71 when the car is removed. Vent 71 is preferably located over the feed pipe in order to permit direct passage of air currents whereby more efficient ventilation is obtained. It is to be noted that by providing an upper automatic seal only a single hand control is necessary for completely sealing the calcine car against loss of dust.

While certain novel features of the invention have been shown and described and are pointed out in the annexed claims, it will be understood that various omissions, substitutions and changes in the forms and details of

the device illustrated and in its operation may be made by those skilled in the art without departing from the spirit of the invention.

5. What is claimed is:

1. In combination with a material conveyor, a discharge spout terminating in a substantially horizontal surface, a stationary feed pipe positioned below said conveyor and having a telescopic member in communication therewith and a flanged member carried by said telescopic member and adapted to contact with said horizontal surface, said member being adapted to accommodate itself to angular displacement whereby a tight seal with said horizontal surface is automatically effected, and means for elevating said telescopic member comprising a pivoted member and a lever for controlling the position of said pivoted member.

2. In combination with a furnace feed pipe, a slidable member mounted therein, a pivoted lever pivotally connected to said slidable member, and means for causing pivotal movement of said lever comprising a pair of links forming a toggle joint, one of said links being resiliently secured to said lever.

3. In combination with a stationary feed pipe, an extensible member slidably mounted thereon, a pivoted lever, links connecting said lever to said extensible member, means for controlling the position of said lever including a rod pivoted thereto, a link slidably carried in said rod, resilient means for maintaining said link in operative position, and means cooperating with said link for controlling the position thereof.

4. In combination with a movable car adapted to receive material, said car having a cover provided with an opening, a stationary pipe positioned in alignment with said opening when said car is in material discharging position, said pipe and said cover having engaging surfaces and resilient means for holding said surfaces in engagement for automatically forming a seal with said pipe when said car is positioned thereunder.

5. In combination with a movable car adapted to receive material, said car having a cover provided with an opening, an upstanding flange surrounding said opening, a framework slidably carried in said flange, and resilient means for maintaining said framework in an elevated position whereby a tight seal is automatically effected with a stationary pipe when said car is positioned thereunder.

6. In combination with a movable car adapted to receive material, said car having a cover provided with an opening, an upstanding flange surrounding said opening, a framework slidably carried in said flange and having a downwardly inclined portion whereby said frame may be automatically operated by a stationary pipe when said car

is positioned thereunder, and resilient means for maintaining said framework in an elevated position whereby a tight seal is automatically effected with said pipe.

7. In combination with a calcine car, a downwardly extending discharge spout having a horizontal flange, a stationary feed pipe, means for effecting a seal between said feed pipe and said flange comprising a slideable member carried by said feed pipe, a flanged member pivotally secured to said slideable member, means for elevating said slideable member for effecting a seal, a stationary vent pipe positioned over said car, said car being provided with a cover having an opening adapted to align with said vent pipe, a framework carried by said cover and surrounding said opening, and resilient means for maintaining said framework in an elevated position whereby said framework automatically seats upon said vent pipe for forming a seal.

8. In combination with a furnace having a charge pipe, a movable receptacle having a discharge spout adapted to register with said charge pipe when said receptacle is brought into material discharging position, means for effecting a seal between said discharge spout and said charge pipe, said receptacle having a cover provided with a vent opening, a stationary vent pipe adapted to register with said opening when the receptacle is in material discharging position, and automatic means for effecting a seal between said cover and said vent pipe comprising cooperating surfaces carried by said cover and said vent pipe and resilient means for holding said surfaces in engagement.

9. In combination with a furnace having a charge pipe, a movable receptacle having a discharge spout adapted to register with said charge pipe when said receptacle is brought into material discharging position, means for effecting a seal between said discharge spout and said charge pipe, said receptacle having a cover provided with a vent opening, a stationary vent pipe adapted to register with said opening when the receptacle is in material discharging position, automatic means for effecting a seal between said cover and said vent pipe comprising a slideable framework carried by said cover and resilient means for maintaining said framework in engagement with said vent pipe.

10. In combination with a furnace having a charge pipe, a stationary vent pipe, a movable receptacle for discharging material into said furnace, means automatically operable upon bringing said receptacle into discharging position for effecting a seal with said vent pipe comprising cooperating surfaces carried by said vent pipe and said receptacle and resilient means for holding said surfaces in engagement, and manually operable means

for effecting a seal with said furnace charge pipe.

11. In combination with a furnace having a charge pipe, a stationary vent pipe, a movable receptacle for discharging material into said furnace and means automatically operable upon bringing said receptacle into discharging position for effecting a seal with said vent pipe said means comprising cooperating surfaces carried by said vent pipe and said receptacle and resilient means for maintaining said surfaces in engagement.

In testimony whereof I have hereunto set my hand.

BENJAMIN GEORGE CALL.
